BY
Augustus B. S. Troughton.

ATTORNEY.

UNITED STATES PATENT OFFICE.

WALTER H. BANCROFT, OF BRYN ATHYN, PENNSYLVANIA.

MANUFACTURE OF ALKALINE SECONDARY OR STORAGE BATTERIES.

Application filed June 18, 1925. Serial No. 37,962.

Some electrodes or plates include units comprising a perforated metallic envelope containing metallic strips arranged face to face in confronting relation with active material or material to become active between the middle portions of the strips leaving the ends bare, and the bare ends of the strips and the wall of the envelope are pinched together.

10 The principal object of the present invention is to facilitate the manufacture of such units, and more particularly to provide bare ends of the strips for pinching while at the same time facilitating the application of the 15 active material or material to become active.

According to my invention the metallic strips are assembled face to face in a pile and active material or material to become active is dusted upon them with suitable 20 consolidation or tamping. Thus the active material or material to become active extends substantially throughout the unit. The 25 assemblage may then be arranged in a fixture and the ends of the strips bared by washing them with a strong jet of, for example, a solution of potassium hydroxide or the like, or the assemblage may be arranged in its perforated metallic envelope and the 30 ends of the strips bared by dipping them in a suitable bath, as of a solution of potassium or the like, and then pinching or squeezing the ends of the assemblage.

In the drawings—

Figure 1 is a top or plan view of one of 35 the units.

Fig. 2 is a cross-section thereof drawn to an enlarged scale.

Fig. 3 is a diagrammatic view showing part 40 of the envelope broken away and illustrating one way of washing the active material or material to become active.

Fig. 4 is a similar view illustrating another way of washing the active material or material to become active.

45 Fig. 5 is a sectional view representative of end pinching or squeezing means, and

Fig. 6 is a sectional view showing the bared ends of the strips and the wall of the tube pinched as in the finished unit.

In the drawing 1 is a perforated metallic 50 envelope or tube, 2 are bands that may encircle and reinforce it, 3 are metallic strips shown as conterminous with the envelope, and 4 is active material or material to become active. In the finished unit, Fig. 6, 5 55 indicates the bare ends of the strips which along with the wall of the envelope are pinched together. 6 is a bath into which a portion of the unit may be dipped as one way of washing its active material or material to become active, and 7 indicates a press mold for squeezing or pinching the 60 dipped portions of the units to express or exude active material or material to become active and to bare the ends of the strips. 65 Another way of washing is to subject the end portions to the action of a strong jet or spray for which purpose the units may be mounted in a clamp 8 with their ends, minus their envelopes, exposed to the action of a 70 jet indicated at 9.

It will be obvious to those skilled in the art that modifications may be made in details of procedure without departing from the spirit of my invention which is not limited to such matters or otherwise than as the prior art and the appended claims may require.

I claim:

1. The process of making units for alkaline 80 storage batteries which consists in first washing and then pinching end portions of an assemblage including metallic strips and active material or material to become active arranged between the strips, whereby the 85 pinched portions of the strips are bared.

2. The process of making units for alkaline storage batteries which consists in subjecting the end portions of an assemblage, comprising metallic strips and active material or material to become active arranged between the strips, to the action of a jet; and then pinching the end portions, substantially as described.

WALTER H. BANCROFT.
